RAILWAY SIGNALING SYSTEM

James J. Van Horn, Pittsburgh, Pa., assignor to
 The Union Switch & Signal Company, Swiss-
 vale, Pa., a corporation of Pennsylvania

Application October 29, 1942, Serial No. 463,733

8 Claims. (Cl. 246—130)

My invention relates to railway signaling systems and particularly to improved means for controlling the crossing signals at an intersection of a highway with a stretch of single track railroad over which traffic may move in either direction, and which is equipped with signaling apparatus of the type shown in my copending application for Letters Patent of the United States, Serial No. 412,279, filed September 25, 1941, now Patent No. 2,344,333, dated March 14, 1944.

In my application identified above, there is shown a signaling system for a single track railroad over which traffic may move in either direction. The system shown in that application operates without line wires except for the portions of a track stretch adjacent a highway intersection. In the system shown in that application each track section in the track stretch is equipped with two track circuits, one for each direction of traffic. Means are provided to at times supply steady energy to either end of the track stretch, while the track circuits are arranged so that when the track stretch is vacant, this steady energy is cascaded from one section to another throughout the track stretch to energize traffic locking means at the other end of the track stretch and thus permit the direction of traffic in the track stretch to be reversed. In addition, there are means at each end of the track stretch effective after the stretch has been conditioned for either direction of traffic to supply coded energy to the section at the exit end of the track stretch, and the track circuit apparatus for each section is arranged so that this coded energy is cascaded from one section to another to the entrance end of the track stretch to control the signal at the entrance end of the stretch.

As shown in Fig. 4 of my application identified above, where a highway crossing is encountered, track sections employing steady energy track circuits are provided on either side of the intersection to control the highway crossing signals, while a line circuit is provided to carry around the approach sections at the highway crossing the steady and coded energy employed in the rest of the track stretch.

The arrangement shown in my application operates satisfactorily, but as the steady and coded energy employed to control the signals governing traffic in the track stretch is supplied over a line circuit, the operation of the signaling system is dependent on continuity of this line circuit. If for any reason this line circuit is interrupted, the signals for the track stretch will dis-

play stop indications until the line circuit is repaired.

It is an object of my invention to provide for use in a system of the type described improved means to control highway crossing signals.

A further object of my invention is to provide improved means of the type described in which the coded and steady energy employed to control the signals in the track stretch is transmitted through the track rails of the approach sections at a highway intersection instead of over a line circuit extending around these sections.

Another object of my invention is to provide improved means of the type described which are arranged so that the steady or coded energy employed in the control of the signals and supplied to the approach sections operates the track circuit apparatus for these sections to normally maintain the crossing signals inactive, these means being also arranged so that when conditions are such that neither steady nor coded signal control energy is supplied to an approach section, energy of a distinctive character is supplied to such approach section and operates the track circuit apparatus for the section to discontinue operation of the crossing signals when the section is vacated.

A further object of my invention is to provide a system of the type described in which coded energy of a distinctive code frequency is employed in the approach sections to discontinue operation of the highway crossing signals.

Other objects of my invention and features of novelty will be apparent from the following description taken in connection with the accompanying drawings.

I shall describe one form of apparatus embodying my invention, and shall then point out the novel features thereof in claims.

In practicing my invention, I provide each approach section with track circuit apparatus similar to that provided for each of the other track sections in the track stretch, and arrange the track circuits for the approach sections so that on the supply of steady energy or of coded energy of a train governing frequency to either end of an approach section a crossing signal control relay at the other end of the approach section is picked up, while energy of the same type as is supplied to such approach section is supplied to the section adjacent such other end of the approach section. The track circuits for the approach sections are also arranged so that when neither steady nor coded signal control energy is supplied to a section, coded energy of a distinctive code frequency

is supplied to the section rails, and, when the section is vacant, energizes means to prevent operation of the crossing signals, but will not cause energy of this code frequency to be supplied to the rails of the adjacent section.

Referring to Figs. 1A and 1B of the drawings, there is shown therein a stretch of single track railroad over which traffic may move in either direction. The track stretch includes an intersection with a highway and this crossing is protected with suitable crossing signals XS, while the track stretch is provided with means embodying this invention for controlling the crossing signals.

This invention is directed to the apparatus for the approach sections at either side of the highway crossing and to the apparatus at the adjacent ends of the adjoining track sections. This invention is not concerned with the apparatus at other points in the track stretch or at the ends of the single track stretch except insofar as the equipment of this invention is intended to operate in conjunction with that apparatus, and the equipment at those locations may be constructed as shown in my application for Letters Patent of the United States, Serial No. 412,279.

In order to simplify the disclosure and facilitate understanding of my invention, only the equipment for the approach sections and for the adjacent ends of the adjoining sections has been shown in the drawings.

The rails 1 and 1a of the track stretch are divided by means of the usual insulated rail joints 3 into a number of track sections. Each of these sections is identified by the reference character T with a distinguishing numerical prefix which also identifies the apparatus associated with that section.

To facilitate description of the equipment it will be assumed that the right-hand end of the track stretch is east and that the left-hand end of the stretch is west, so that train movements from left to right are eastbound and train movements from right to left are westbound.

The track section 9T is a relatively short section which includes the highway intersection. This section has at one side the eastbound approach section 8T, and at the other side the westbound approach section 10T, while means governed by traffic conditions in these sections are provided to control the relay XR which governs the crossing signals XS.

The short intermediate section 9T is provided for the purpose of insuring that on movement of a train through the track stretch in either direction, operation of the crossing signals will be continued until the train clears the intersection. If this method of operation of the crossing signals is not required, the intermediate section 9T may be omitted and the approach sections 8T and 10T may adjoin.

In the system shown in the drawings the control relays WTM and ETM, and the directional stick relays WSR and ESR, cooperate with the track relay 9TR of the intermediate section 9T to control the relay XR which governs the crossing signals XS. However, the invention is not limited to the use of this form of crossing signal control apparatus and an interlocking relay of well-known construction, or other appropriate apparatus, may be employed to control the crossing signals.

The section 9T is provided with a track circuit of the conventional type employing steady en-

ergy, while the steady and coded energy employed in the control of traffic in the track stretch is transmitted between the approach sections through local wiring.

5 Each of the approach sections is, in effect, provided with two track circuits, one eastbound and one westbound. These track circuits are similar in arrangement and operation to the track circuits employed in the track sections of 10 the system shown in my application identified above. Each track circuit for each section includes a code following track relay TR at one 15 end of the section and a source of energy, such as a battery TB, at the other end of the section. In addition, each approach section has at each end thereof a steady energy detecting track relay TRA.

Each track section also has at each end thereof a coding relay CTM having contacts controlling connection of the associated track battery and track relays across the section rails.

20 Each of the code following track relays TR has associated therewith a front contact repeater relay FSA, and a back contact repeater relay BSA. The relays FSA and BSA are of a type 25 the contacts of which are slow to release, while each of these relays may have a snubbing resistor connected across the terminals of its winding to increase the release period of the relay. 30 The relays FSA and BSA are proportioned so their contacts will remain picked up throughout the longest code interval during which the supply of energy to the relay is interrupted.

The code following track relays 8WTR and 35 10ETR at the ends of the approach sections 8T and 10T adjacent the highway intersection have associated therewith code detecting relays CDR which are energized through decoding transformers DT. The relays CDR and the 40 formers DT are proportioned so that the relays will not become picked up when the associated track relay is following coded energy of a low code frequency, such as 20 code frequency, which is employed for detection purposes, but will be 45 come picked up when the track relay is following coded energy of a higher code frequency, such as 75 or 180 code frequency, which is employed for traffic governing purposes.

Each approach section has at the end thereof 50 remote from the highway intersection a coding device 20CT having a contact which, when the device is energized, is opened and closed at a rate such as to supply 20 code impulses a minute which are separated by periods of equal duration in which no energy is supplied.

The relays and other equipment except the track relays are supplied from suitable sources of direct current, such as storage batteries, located at appropriate points in the track stretch. The 60 terminals of these sources are designated B and C in the drawings.

The equipment is shown in the condition which it assumes when the track stretch is vacant and steady energy is supplied at the east end of the 65 track stretch. As explained in my application identified above, steady energy is supplied at the east end of the track stretch and is cascaded from one track section to another to the west end of the stretch to energize traffic locking 70 means to permit the stretch to be conditioned for passage of an eastbound train through the track stretch.

The track circuit apparatus provided by this 75 invention for the approach sections is arranged so that on the supply of steady energy to either

end of the stretch, it will be cascaded through the approach sections to the portion of the track stretch at the other side of these sections, while the steady energy supplied through the approach sections causes the track circuit apparatus for the approach sections to operate to maintain the crossing signals inactive.

As steady energy is supplied to the east end of section 11T, this energy feeds over back contacts 20 and 21 of coding relay 11ECTM to track relay 11ETR and keeps its contacts picked up so contact 23 establishes a circuit to supply energy to relay 11EFSA, but does not establish the circuit to supply energy to relay 11EBSA. Accordingly, relay 11EFSA is picked up and relay 11EBSA is released so steady uncoded energy is supplied over front contact 25 of relay 11EFSA and back contact 26 of relay 11EBSA to coding relay 10WCTM. The contacts 27 and 28 of this relay, therefore, are steadily picked up to connect the track battery 10ETB across the rails of section 10T and cause steady energy to be supplied to this section. In addition, as the contacts of relay 10WCTM are steadily picked up, track relays 10WTR and 10WTRA are not connected to the section rails and remain released.

The steady energy supplied to the rails of section 10T feeds over back contacts 30 and 31 of coding relay 10ECTM to track relays 10ETR and 10ETRA and causes the contacts of these relays to be steadily picked up so contact 32 of relay 10ETR establishes the circuit of relay 10EFSA but does not establish the circuit of relay 10EBSA. Accordingly, relay 10EBSA is released and its back contact 33 establishes the circuit of relay 10ETRA, while its contact 34 interrupts the circuit of the primary winding of the decoding transformer 10EDT to prevent consumption of energy by this transformer at this time.

As relay 10ETRA is picked up, its contacts 35 and 36 establish a circuit to supply energy to the relay ETM, while its front contact 37 establishes a circuit including front contact 38 of track relay 9TR for supplying steady energy to coding relay 8WCTM.

As steady energy is supplied to relay 8WCTM, its contacts 40 and 41 are picked up and interrupt connection from the track rails to track relays 8WTR and 8WTRA, while these contacts connect the track battery 8ETB across the section rails and steady energy is supplied over back contacts 43 and 44 of coding relay 8ECTM to track relays 8ETR and 8ETRA.

As track relay 8ETR is steadily picked up, its front contact 45 establishes the circuit to supply energy to relay 8EFSA, but does not establish the circuit to supply energy to relay 8EBSA, and contact 46 of relay 8EBSA is released and establishes the circuit of relay 8ETRA. As relay 8ETRA is energized, its contacts 47 and 48 establish a circuit to supply energy to relay WTM, while as relays 8ETR and 8EFSA are both energized, steady energy is supplied over front contact 52 of relay 8ETR and front contact 53 of relay 8EFSA to coding relay 7WCTM so that its contacts 50 and 51 are picked up and connect the track battery 7ETB across the rails of section 7T. This causes steady energy to be supplied to section 7T from which the supply of steady energy is repeated throughout the other track sections to the west end of the single track stretch.

As relays ETM and WTM are picked up, and as track relay 9TR is also picked up, energy is supplied to the relay XR over the circuit which

includes front contact 55 of relay 9TR, front contact 58 of relay WTM, and front contact 51 of relay ETM. The relay XR, therefore, is energized and its contact 58 is picked up and interrupts the circuit of the crossing signals so these signals are inactive at this time.

If it is desired to condition the stretch to permit a westbound train to pass through the stretch, means, not shown, at the right-hand or 10 east end of the stretch are operated to permit clearing of the westbound signal governing entrance of trains into the stretch and to cut off the supply of steady energy to the west end of the stretch. When the supply of steady energy 15 to the stretch is interrupted, the track relay for each section releases and cuts off the supply of steady energy to the adjoining section so the supply of steady energy is cut off from the various sections in succession throughout the track 20 stretch including the approach sections, while the contacts of the coding relays CTM are released and connect the associated track relays across the section rails.

When the supply of steady energy at the west 25 end of the stretch is cut off, apparatus, not shown, at that location causes coded energy of suitable code frequency, such as 75 or 180 code frequency, to be supplied to the west end of the stretch. The means for causing coded energy to be supplied 30 to the west end of the stretch are not a part of this invention, and are shown and described in my application identified above.

On the supply of coded energy to the west end 35 of the track stretch, coded energy is cascaded through the successive track sections to section 7T so that coded energy is supplied over back contacts 50 and 51 of coding relay 7WCTM to track relay 7WTR. Accordingly, this relay follows code and energy as supplied over the front point of 40 its contact 55 to relay 7WFSA, and is supplied over the back point of its contact 55 and front contact 56 of relay 7WFSA to relay 7WSA.

On picking up of relay 7WFSA, its contact 57 45 interrupts the circuit for supplying energy of 20 code frequency to coding relay 8ECTM, (the manner in which 20 code is supplied will be explained in detail hereinafter), while on picking up of relay 7WSA its front contact 58 establishes a circuit including front contact 60 of relay 7WTR for supplying energy to relay 8ECTM so that the energy supplied to the coding relay 8ECTM is coded at the same frequency as the energy supplied to section 7T, and the relay 8ECTM causes coded energy of this frequency to be supplied to 55 the west end of section 8T.

In addition, on picking up of relays 7WFSA and 7WSA their contacts 61 and 62 interrupt the circuit of the code transmitter 20CT at this location and it ceases to operate.

60 The coded energy supplied to the west end of section 8T feeds over back contacts 40 and 41 of coding relay 8WCTM to relay 8WTR. When relay 8WTR follows code, energy is supplied over the front point of its contact 64 to relay 8WFSA, 65 and is supplied over the back point of its contact 64 and front contact 65 of relay 8WFSA to relay 8WBSA. On picking up of relay 8WBSA, its back contact 66 interrupts the circuit of relay 8WTRA and its front contact 66 connects the resistance 70 67 in multiple with track relay 8WTR. The resistance 67 is of substantially the same value as the winding of relay 8WTRA so the track circuit characteristics are substantially the same whether or not track relay 8WTRA is included 75 in the track circuit.

On picking up of relay 8WBSA, its contacts 73 and 74 establish a circuit to supply energy to crossing signal control relay WTM. In addition, on picking up of relay 8WBSA its contact 69 establishes the circuit including contact 78 of relay 8WTR for supplying energy to the primary winding of decoding transformer 8WDT so that on continued code following operation of relay 8WTR energy effective to pick up the contact of relay 8WCDR is supplied through the decoding transformer to relay 8WCDR, while this energy is rectified by contact 71 of relay 8WTR in the manner explained in Letters Patent of the United States No. 2,237,788, granted to Frank H. Nicholson and Leslie R. Allison on April 8, 1941.

On the supply of energy to relay 8WCDR, its contact 75 is picked up and establishes a circuit to supply coded energy to relay 10ECTM. This circuit is traced from terminal B through front contact 76 of relay 8WTR, front contact 75 of relay 8WCDR, back contact 78 of relay 8WTRA, wire 79, front contact 80 of relay 9TR, and winding of relay 10ECTM to terminal C. As the circuit for supplying energy to relay 10ECTM includes a contact of the code following track relay 8WTR, the energy supplied to relay 10ECTM is coded at the same rate as the energy supplied to section 8T, and relay 10ECTM causes coded energy of this code frequency to be supplied to the west end of section 10T.

The coded energy supplied to the west end of section 10T feeds over back contacts 27 and 28 of relay 10WCTM to relay 10WTR and causes code following operation of this relay. On picking up of contact 83 of relay 10WTR energy is supplied to relay 10WFSA, while on release of contact 83 of relay 10WTR energy is supplied to relay 10WBSA over the circuit which includes front contact 84 of relay 10WFSA.

On picking up of relay 10WBSA its contacts 86 and 87 establish a circuit to supply energy to crossing signal control relay ETM. On picking up of relay 10WFSA its contact 88 interrupts the circuit for supplying energy of 20 code frequency to relay 10WCTM, while its contact 89 interrupts the circuit for supplying energy to the code transmitter 20CT at this location. In addition, on picking up of relay 10WFSA its contact 90 establishes a circuit including front contact 91 of code following track relay 10WTR for supplying energy to coding relay 11ECTM and this relay operates to supply coded energy to the west end of section 11T, while the track circuit apparatus, not shown, for section 11T causes this coded energy to be repeated into the adjacent section. Similarly, coded energy is supplied through the other sections until the east end of the stretch is reached, and the coded energy supplied to this point will cause the head-block signal at that point to display a proceed indication and thus permit a westbound train to enter the track stretch.

It will be seen, therefore, that on the supply of coded energy to the west end of the track stretch, this coded energy is cascaded through the approach sections associated with the highway crossing, and that the track circuit apparatus for these sections operates to maintain circuits for the crossing signal control relays WTM and ETM so that they maintain a circuit for relay XR to cause it to keep the crossing signals inactive.

The relays WTM and ETM are of a type the contacts of which are slow to release so that the contacts of these relays remain picked up dur-

ing periods in which the supply of energy thereto is momentarily interrupted, as may occur on a change from the supply of steady energy at one end of the track stretch to the supply of coded energy at the other end of the track stretch.

Operation of equipment on movement of a west-bound train through the track stretch

When a westbound train enters the track stretch, it shunts the rails of each section it enters, and thus cuts off the supply of coded energy to the sections in the rear. Accordingly, as soon as a westbound train enters the track stretch, the supply of coded energy to the equipment at the east end of the stretch is cut off and the signal governing entrance of westbound trains into the stretch is caused to display its stop indication.

In addition, when the supply of coded energy to the east end of the track stretch is cut off, the equipment at that location operates as described in my application referred to above to cause steady energy to be supplied to the east end of the track stretch, unless the remote control apparatus has been operated to cause the signal at the east end of the track stretch to be re-cleared on the subsequent supply of coded energy to the equipment controlling that signal.

When the westbound train enters section 10T, it shunts the track relay 10WTR so that its contact 83 thereafter remains released and does not establish the circuit to supply energy to relay 10WFSA which releases so its contact 84 interrupts the circuit of relay 10WBSA to release that relay and cause its contacts 86 and 87 to interrupt the supply of energy to relay ETM. Relay ETM, therefore, also releases and its contact 57 interrupts the circuit of relay XR so that back contact 58 of relay XR closes and establishes the circuit of the crossing signals to cause them to operate and warn users of the highway of the approach of a train.

In addition, on release of relay ETM its contact 94 establishes a pick-up circuit for west-bound stick relay WSR. This circuit is traced from terminal B through front contact 95 of relay WTM, back contact 94 of relay ETM, back contact 96 of relay ESR, and winding of relay WSR to terminal C. At this time, therefore, the relay WSR will pick up, and, as hereinafter explained, will establish a circuit for relay XR to discontinue operation of the crossing signals after the train vacates sections 10T and 9T.

When relay 10WFSA released, its contact 90 interrupted the circuit of relay 11ECTM, while its contact 88 established the circuit including back contact 98 of relay 11EFSA and back contact 99 of relay 11EBSA for supplying energy to code transmitter 20CT so this device starts to operate.

In addition, when relay 10WFSA released, its contact 88 established the circuit including a contact of code transmitter 20CT as well as back contact 25 of relay 11EFSA and back contact 26 of relay 11EBSA for supplying energy of 20 code frequency to relay 10WCTM. This relay, therefore, operates to cause energy of 20 code frequency to be supplied to the east end of section 10T, but as long as this section is occupied, this energy does not reach track relay 10ETR.

When the westbound train enters section 9T, track relay 9TR releases and its contact 55 additionally interrupts the circuit of relay XR, and establishes a stick circuit including front contact 100 of relay WSR to keep relay WSR ener-

gized after release of relay WTM. In addition, on release of relay 9TR, its contact 38 interrupts the circuit of coding relay 8WCTM, while its contact 80 interrupts the circuit of coding relay 10ECTM so that these coding relays are certain to remain released and connect the associated track relays across the section rails.

When the train enters section 8T, it shunts relay 8WTR and relays 8WFSA, 8WBSA and 8WCDR release. On release of relay 8WBSA its contacts 73 and 74 interrupt the supply of energy to the relay WTM and this relay releases and its contact 56 additionally interrupts the circuit of relay XR.

When the train enters section 7T, track relay 7WTR is shunted and energy is no longer supplied to relays 7WFSA and 7WBSA and these relays release to establish the circuit to supply energy to the associated code transmitter 20CT and to supply energy of 20 code frequency to the relay 8ECTM so that it operates to supply energy of 20 code frequency to the west end of section 8T. The circuit for supplying energy to the code transmitter includes back contact 62 of relay 7WBSA, back contact 61 of relay 7WFSA, and back contact 110 of relay 8EFSA, while the circuit for supplying energy to coding relay 8ECTM includes a contact of the code transmitter 20CT, back contact 112 of relay 8EFSA, back contact 57 of relay 7WFSA, and back contact 58 of relay 7WBSA.

For purposes of illustration it will be assumed that the remote control apparatus governing the signal at the east end of the stretch and controlling entrance of westbound trains into the track stretch has been operated to re-clear this signal so that the equipment associated with that signal does not operate to supply steady energy to the east end of the track stretch. Accordingly, as the train vacates each section, both of the track circuits for that section remain deenergized, and when the train vacates section 11T, relays 11EFSA and 11EBSA remain released and maintain the circuits for supplying energy to the code transmitter 20CT, and for supplying energy of 20 code frequency to the coding relay 10WCTM.

When the train vacates section 10T, the energy of 20 code frequency supplied to the east end of this section feeds over back contacts 30 and 31 of relay 10ECTM to relay 10ETR so that contact 32 of relay 10ETR causes energy to be supplied to relays 10EFSA and 10EBSA. On picking up of relay 10EBSA its contacts 102 and 103 establish a circuit to supply energy to relay ETM and the contacts of this relay pick up so that contact 57 permits energy to be supplied to relay XR after section 9T is vacated, while front contact 94 of relay ETM establishes a stick circuit for relay WSR. This circuit includes front contact 94 of relay ETM, back contact 95 of relay WTM, and front point of contact 105 of relay WSR, and keeps relay WSR picked up after the train vacates section 9T and relay 9TR picks up.

On picking up of relay 10EBSA, its contact 34 establishes the circuit of the primary winding of decoding transformer 10EDT, and energy is supplied through this transformer to relay 10ECDR. However, as pointed out above, the transformer 10EDT and the relay 10ECDR are so designed and proportioned that the relay 10ECDR will not pick up when the relay 10ETR is following energy of 20 code frequency. Accordingly, contact 106 of relay 10ECDR remains released and interrupts the circuit of relay

8WCTM and the coding relay 8WCTM remains released and connects the relay 8WTR across the rails of section 8T.

In addition, on picking up of relay 10EBSA its contact 33 interrupts the circuit of relay 10ETRA and connects a resistor 107 in multiple with relay 10ETR.

When the train vacates section 9T, track relay 9TR picks up and interrupts one stick circuit for relay WSR, but this relay is held picked up by energy supplied over the stick circuit which includes front contact 94 of relay ETM, back contact 95 of relay WTM, and front contact 105 of relay WSR.

On picking up of relay 9TR, energy is supplied to relay XR over the circuit which is traced from terminal B through front contact 55 of relay 9TR, front contact 108 of relay WSR, front contact 57 of relay ETM, and winding of relay XR to terminal C. The relay XR, therefore, picks up and its contact 58 cuts off the supply of energy to the crossing signals XS and operation of these signals is discontinued.

When the train advances far enough to vacate section 8T, the energy of 20 code frequency supplied at the west end of this section feeds to the track relay 8WTR and produces code following operation of this relay with the result that energy is supplied to relays 8WFSA and 9WBSA. On picking up of relay 8WBSA, its contact 66 interrupts the circuit of relay 8WTRA, while its contact 69 establishes the circuit of the primary winding of transformer 8WDT and energy is supplied through this transformer to relay 8WCDR, but as relay 8WTR is following energy of 20 code frequency, the relay 8WCDR remains released. As relay 8WCDR remains released, its contact 75 interrupts the circuit of coding relay 10ECTM and that relay is certain to remain released and connect relay 10ETR across the rails of section 10T.

When relay 9WBSA picks up, its contacts 73 and 74 establish a circuit to supply energy to relay WTM and contact 56 of this relay is picked up and establishes the originally traced circuit for supplying energy to relay XR, while contact 95 of relay WTM interrupts the stick circuit for relay WSR so relay WSR releases with the result that its contact 105 additionally interrupts the stick circuit for the relay, while its contact 108 interrupts the circuit over which energy was supplied to relay XR prior to picking up of relay WTM.

When the train advances far enough to vacate the track stretch, coded energy may again be supplied to the west end of the track stretch and will be cascaded through the successive track sections to section 7T where it will cause code following operation of the track relay 7WTR with the result that energy is supplied to relays 7WFSA and 7WBSA.

On picking up of relay 7WFSA its back contact 57 interrupts the circuit for supplying energy of 20 code frequency to coding relay 8ECTM, while on picking up of relay 7WBSA its front contact 58 establishes the circuit including front contact 69 of relay 7WTR for supplying energy to the relay 8ECTM. Accordingly, the relay 8ECTM now operates to supply to section 8T coded energy of the same code frequency as that supplied to the west end of the track stretch. The code frequency of this energy is much higher than that of the energy of 20 code frequency previously supplied to section 8T. On the supply of this energy of higher code frequency to track relay

8WTR, relays 8WFSA and 8WBSA are maintained energized, while sufficient energy is now supplied through the decoding transformer 8WDT to relay 8WCDR to pick up that relay so that contact 75 of relay 8WCDR establishes the circuit including front contact 76 of relay 8WTR, back contact 78 of relay 8WTRA, and front contact 80 of relay 9TR for supplying energy to relay 10ECTM. Accordingly, relay 10ECTM now operates at the same rate as relay 8WTR and causes energy of the same code frequency to be supplied to the west end of section 10T as is supplied to the west end of section 8T.

At this time, as previously explained, the relay 10WCTM at the east end of section 10T is being operated at a rate such as to cause energy of 20 code frequency to be supplied to the east end of section 10T.

On the supply of energy of 75 or 180 code frequency to the west end of section 10T, this energy feeds to track relay 10WTR during the periods in which the contacts of relay 10WCTM are released. Because of the substantial difference in the code frequency of the energy supplied to the two ends of the section there are frequently recurring intervals when the contacts of relay 10ECTM are picked up and the contacts of relay 10WCTM are released. Furthermore, the released periods of the relay 10WCTM are relatively long so that more than one impulse of coded energy may be supplied to the relay 10WTR during one released period of the contacts of relay 10WCTM.

On the supply of coded energy to relay 10WTR, its contacts pick up and establish a circuit to supply energy to relay 10WFSA so that the contacts of relay 10WFSA pick up with the result that its contact 88 cuts off the supply of energy of 20 code frequency to coding relay 10WCTM so that the contacts of this relay thereafter remain released and maintain the circuit of relay 10WTR.

As the contacts of relay 10WCTM remain released, energy is no longer supplied to the east end of section 10T and relay 10ETR remains released so that relays 10EFSA and 10EBSA release. On release of relay 10EBSA its contacts 102 and 103 interrupt the supply of energy to relay ETM, but this relay is of a type which is slow in releasing so it remains picked up until after contacts 86 and 87 of relay 10WBSA pick up and established a circuit to supply energy to relay ETM.

In addition, on picking up of relay 10WFSA its contact 89 interrupts the circuit for supplying energy to the code transmitter 20CT, while its contact 90 establishes the circuit including front contact 91 of relay 10WTR for supplying energy to coding relay 10ECTM so that it operates to supply to section 11T energy of the same code frequency as is supplied to section 10T.

On release of relay 10WTR subsequent to picking up of relay 10WFSA, energy is supplied to relay 10WBSA and it picks up so that its contacts 86 and 87 establish a circuit to supply energy to relay ETM and thus maintain the crossing signals inactive.

On operation of relay 10ECTM to supply coded energy to section 11T, coded energy is cascaded through any other track sections to the east end of the stretch where it operates suitable equipment controlling the headblock signal and causes it to condition the headblock signal to display a proceed indication.

If when the westbound train under consideration passes through the track stretch, the remote

control apparatus has not been conditioned to re-clear the headblock signal governing entrance of westbound trains into the track stretch, the equipment associated with that headblock signal will operate, as described in my application identified above, to supply steady energy to the east end of the stretch after entrance of the train into the stretch.

In the event that steady energy is supplied to the east end of the stretch, as the train vacates each section energy will be cascaded through the successive sections to section 11T, and when section 11T is vacated, this steady energy will be supplied over back contacts 20 and 21 of relay 11ECTM to relay 11ETR so that its front contact 23 establishes the circuit to supply energy to relay 11EFSA.

On picking up of relay 11EFSA, its contact 25 cuts off the supply of energy of 20 code frequency to relay 10WCTM and establishes the circuit including back contact 26 of relay 11EBSA for supplying steady energy to relay 10WCTM. Accordingly, the contacts of relay 10WCTM are held picked up and cause steady energy to be supplied to the east end of section 10T and prevent the supply of energy to relay 10WTR so that it remains released.

As relay 10WTR remains released, relay 10WFSA also remains released and the circuit of relay 10ECTM is interrupted so that it remains released and maintains the circuit of relay 11ETR with the result that relay 11ETR remains picked up and maintains the circuit of relay 11EFSA so that it maintains the supply of steady energy to coding relay 10WCTM.

When the train vacates section 10T, steady energy supplied at the east end of section 10T feeds over back contacts 30 and 31 of relay 10ECTM to track relays 10ETR and 10ETRA and picks up the contacts of these relays. When relay 10ETRA picks up, its contact 37 establishes a circuit to supply steady energy to coding relay 8WCTM and the contacts of relay 8WCTM pick up to cause steady energy to be supplied to the east end of section 8T and to prevent the supply of energy to track relay 8WTR. Accordingly, relays 8WTR and 8WCDR remain released and energy is not supplied to relay 10ECTM so it remains released and maintains the circuits of relays 10ETR and 10ETRA energized with the result that contact 37 of relay 10ETRA is maintained picked up and maintains the circuit for supplying steady energy to relay 8WCTM.

In addition, on picking up of relay 10ETRA its contacts 35 and 36 establish a circuit to supply energy to the relay ETM so relay ETM picks up, and, as explained above, establishes a circuit to supply energy to relay XR when section 9T is vacated to thereby discontinue operation of the crossing signals.

As relay 8WTR remains released, the relays 8WFSA, 8WBSA and 8WCDR are released so that contacts 73 and 74 of relay 8WBSA interrupt the supply of energy to relay WTM.

As coding relay 8WCTM is supplied with steady energy, its contacts 40 and 41 connect the track battery 8ETB across the section rails and when the train vacates section 8T, energy feeds over back contacts 43 and 44 of relay 8ECTM to relays 8ETR and 8ETRA so that the contacts of these relays pick up. On picking up of relay 8ETRA, its contacts 47 and 48 establish a circuit to supply energy to relay WTM, with the result that relay 75 WTM interrupts the stick circuit for relay WSR

and establishes a circuit to supply energy to relay **XR** as explained above.

On picking up of relay **8ETR**, its contact **45** establishes a circuit to supply energy to relay **8EFSA** so that it picks up and energy is supplied over front contact **52** of relay **8ETR** and front contact **53** of relay **8EFSA** to coding relay **7WCTM**.

Accordingly, relay **7WCTM** picks up and its contacts **50** and **51** connect the battery **7ETB** across the section rails and prevent the supply of energy to relay **7WTR** so relays **7WTR** and **7WFSA** remain released and do not establish the circuit for supplying energy to relay **8ECTM**. The relay **8ECTM**, therefore, remains released and maintains the circuit of relays **8ETR** and **8ETRA** and these relays maintain the supply of energy to relay **7WCTM**.

The steady energy supplied to section **7T** will cause steady energy to be cascaded throughout the remainder of the track sections to the west end of the stretch where the steady energy may be employed to release suitable traffic locking means.

The operation of the equipment when steady energy is supplied at the east end of the stretch and during movement of a westbound train through the track stretch has been explained. The operation of the equipment when steady energy is supplied at the west end of the track stretch, and during movement of an eastbound train through the track stretch, is similar to that described and in order to simplify the disclosure will not be traced in detail.

From the foregoing it will be seen that the track circuit apparatus provided by this invention for the approach sections on either side of a highway crossing operates to cascade either steady energy or coded traffic governing energy through the track stretch when energy of these types is supplied to either end of the track stretch, and that when the track circuit apparatus of the approach sections is responding to energy of either of these types, it operates to maintain the crossing signals inactive.

In addition, it will be seen that when conditions are such that neither steady energy nor coded traffic governing energy is supplied to an approach section, energy of a distinctive code frequency is supplied to the section rails to detect when the section is vacated and to discontinue operation of the crossing signals, but that this type of coded energy will not be repeated into an adjoining section.

Furthermore, it will be seen that the approach section track circuit apparatus provided by this invention is arranged so that on the supply of steady energy or of coded energy of traffic governing frequency to an approach section at a time when energy of 20 code frequency is being supplied thereto, the supply of energy of 20 code frequency over the section rails is cut off and the track circuit apparatus for the section thereafter operates in the usual manner to supply steady energy or coded traffic governing energy to an adjoining section.

Although I have made reference to my copending application identified hereinbefore and showing a remotely controlled single track system with which my present invention may advantageously be used, it will be understood that my invention is not limited to such use, and an understanding of that system, although helpful, is not essential for an understanding of the present invention since an appreciation that

either steady energy or traffic governing code will be supplied at the left-hand end of section **7T** or the right-hand end of section **11T**, depending upon the traffic direction, is all that is required when taken with the detailed description presented herein for a clear understanding of the operation. The particular apparatus for supplying the steady energy and the traffic governing code to sections **7T** and **11T** forms no part of my present invention and accordingly has not been illustrated in order to simplify the disclosure.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In crossing signal control apparatus for a stretch of railway track over which traffic may move in either direction and including an intersection with a highway, the rails of said stretch being divided by insulated joints into a plurality of track sections including a first approach section at one side of the intersection and a second approach section at the other side of the intersection, the track stretch being equipped with traffic governing signaling apparatus of a type in which steady or coded energy of a traffic governing frequency is supplied at one end of the track stretch at given times and is supplied at the other end of the track stretch at other times, each of the track sections in said track stretch being equipped with track circuit apparatus effective when energy is supplied to a vacant section at either end thereof and such energy is supplied steadily or is coded at a traffic governing frequency to cause energy of the same type to be supplied to the corresponding end of the track section adjacent the opposite end of said vacant section, each of said approach sections being equipped with means effective when neither steady energy nor coded energy of a traffic governing frequency is supplied to such section to cause energy of a distinctive code frequency to be supplied to the rails of such section, a crossing signal for said intersection, and means responsive to the supply of steady energy or of coded energy of said traffic governing frequency or of said distinctive code frequency over the rails of said approach sections for controlling said crossing signal.

2. In crossing signal control apparatus for controlling the signal at the intersection between a highway and a stretch of railroad track over which traffic may move in either direction, the rails of said track stretch being divided by insulated joints into a plurality of track sections including a first approach section at one side of the intersection and a second approach section at the other side of the intersection, said track stretch being equipped with traffic governing apparatus of a type in which steady energy or coded energy of a traffic governing frequency is supplied to one end of the track stretch at given times and is supplied to the other end of the track stretch at other times, each track section in said track stretch being provided with track circuit apparatus effective when energy is supplied to a vacant section at either end thereof and such energy is supplied steadily or is coded at a traffic governing frequency to cause energy of the same type to be supplied to the corresponding end of the track

section adjacent the opposite end of said vacant section, in combination, means for each of said approach sections effective when neither steady energy nor coded energy of a traffic governing frequency is being supplied over the rails of such section to supply to the rails of such section coded energy of a distinctive code frequency, and means responsive to the supply of steady energy or of coded energy of either said traffic governing frequency or of said distinctive code frequency over the rails of said approach sections for controlling said crossing signals.

3. In crossing signal control apparatus for controlling the signal at the intersection between a highway and a stretch of railroad track over which traffic may move in either direction, the rails of said track stretch being divided by insulated joints into a plurality of track sections including a first approach section at one side of the intersection and a second approach section at the other side of the intersection, the track stretch being equipped with a traffic governing signaling system of a type in which steady energy or coded energy of a traffic governing frequency is at times supplied to the end of the track stretch at said one side of the intersection and is cascaded through the intervening track sections to the end of the first approach section remote from the intersection provided the intervening track stretch is vacant and at other times is supplied to the end of the track stretch at said other side of the intersection and is cascaded through the intervening track sections to the end of the second approach section remote from the intersection provided the intervening track stretch is vacant, each approach section being equipped with track circuit apparatus effective on the supply of steady energy or of coded traffic governing energy to the end of said section remote from the intersection provided the section is vacant to cause energy of the same type to be supplied to the adjacent end of the other approach section, each approach section also being equipped with track circuit apparatus effective on the supply of steady energy or of coded traffic governing energy to the end of said section adjacent the intersection provided the section is vacant to cause energy of the same type to be supplied to the adjacent track section at the end of the approach section remote from the intersection, in combination, a crossing signal for said intersection, means for each approach section effective in the absence of the supply of steady energy or of coded traffic governing energy over the rails of such section to supply coded energy of a distinctive character to the rails of such section, and means responsive to the supply of steady energy, of coded traffic governing energy, or of coded energy of said distinctive character over the rails of said approach sections for controlling said crossing signal.

4. In crossing signal control apparatus for controlling the signal at the intersection between a highway and a stretch of railroad track over which traffic may move in either direction, the rails of said track stretch being divided by insulated joints into a plurality of track sections including a first approach section at one side of the intersection and a second approach section at the other side of the intersection, the track stretch being equipped with traffic governing signaling apparatus which operates in such manner that steady energy or coded energy of a first type is at times supplied to the rails of the first approach section at the end of said section remote from the in-

tersection and at other times is supplied to the rails of the second approach section at the end of said section remote from the intersection, in combination, a crossing signal for said intersection, electroresponsive means for each approach section located at the end of the section adjacent the intersection and governed by energy supplied over the rails of such section, such means for each approach section being effective according as steady energy or coded energy of said first type is supplied thereto to cause steady energy or coded energy of said first type to be supplied to the rails of the other approach section at the end thereof adjacent the intersection, other electroresponsive means for each approach section located at the end of the section remote from the intersection and governed by energy supplied over the rails of such section, such other electroresponsive means for each approach section being effective according as steady energy or coded energy of said first type is supplied thereto to supply steady energy or coded energy of said first type to the adjacent end of the adjoining track section, means for each approach section effective when neither steady energy nor coded energy of said first type is supplied over the rails of such section to supply to the rails of such section coded energy of a second type, and means responsive to the supply of steady energy, or of coded energy of either said first or said second type over the rails of said approach sections for controlling said crossing signal.

5. In crossing signal control apparatus for controlling the signal at the intersection between a highway and a stretch of railroad track over which traffic may move in either direction, the rails of said track stretch being divided by insulated joints into a plurality of track sections including a first approach section at one side of the intersection and a second approach section at the other side of the intersection, the track stretch being equipped with traffic governing signaling apparatus which operates in such manner that steady energy or coded traffic governing energy is at times supplied to the rails of the first approach section at the end of said section remote from the intersection and at other times is supplied to the rails of the second approach section at the end of said section remote from the intersection, in combination, electroresponsive means for each approach section located at the end of the section adjacent the intersection and governed by energy supplied over the rails of such section, such means for each approach section being effective according as steady energy or coded traffic governing energy is supplied thereto to cause steady energy or coded traffic governing energy to be supplied to the rails of the other approach section at the end thereof adjacent the intersection, other electroresponsive means for each approach section located at the end of the section remote from the intersection and governed by energy supplied over the rails of such section, such other electroresponsive means for each approach section being effective according as steady energy or coded traffic governing energy is supplied thereto to cause steady energy or coded traffic governing energy to be supplied to the adjacent end of the adjoining track section, means for each approach section effective when neither steady energy nor coded traffic governing energy is supplied over the rails of such section to supply to the rails of such section energy of a distinctive type, and means responsive to the supply of steady energy, of coded

traffic governing energy, or of energy of said distinctive type over the rails of said approach sections for controlling said crossing signal.

6. In crossing signal control means for use on a stretch of railway track over which traffic may move in either direction, the rails of said stretch being divided by insulated joints into a plurality of successive track sections including a first, a second, a third and a fourth section, the track stretch being intersected by a highway at a point in the stretch in the vicinity of the adjacent ends of the second and third track sections, the track stretch being equipped with a traffic governing signaling system of a type in which steady energy or coded traffic governing energy is at times supplied to the first section at the end thereof remote from the intersection and at other times is supplied to the fourth section at the end thereof remote from the intersection, in combination, a coding device, a source of current, and electroresponsive means at each end of each of said second and third sections and at the ends of the first and fourth sections adjacent the intersection, each of said coding devices having contacts biased to a position in which they connect the associated electroresponsive device across the section rails, means effective according as steady energy or coded traffic governing energy is supplied over the rails of the first section to the electroresponsive means at the end thereof adjacent the second section to energize the coding device at the end of the second section remote from the intersection to cause steady energy or coded traffic governing energy to be supplied to the rails of said second section, means effective according as steady energy or coded energy is supplied over the rails of the fourth section to the electroresponsive means at the end thereof adjacent the third section to energize the coding means at the end of the third section remote from the intersection to cause steady energy or coded traffic governing energy to be supplied to the rails of said third section, the electroresponsive means at the adjacent ends of the second and third sections each being effective according as steady energy or coded traffic governing energy is supplied thereto over the section rails to energize the coding device at the adjacent end of the other section to cause steady energy or coded traffic governing energy to be supplied to the rails of such section, the second and third sections each having associated therewith means effective when neither steady energy nor coded traffic governing energy is supplied over the rails of such section to cause energy of a distinctive character to be supplied to the rails of such section, a crossing signal for said intersection, and means responsive to the supply of steady energy, coded traffic governing energy, or energy of said distinctive character over the rails of said second and third sections for controlling said crossing signal.

7. In crossing signal control means for use on a stretch of railway track over which traffic may move in either direction, the rails of said stretch being divided by insulated joints into a plurality of successive track sections including a first, a second, a third and a fourth section, the track stretch being intersected by a highway at a point in the stretch in the vicinity of the adjacent ends of the second and third track sections, the track stretch being equipped with a traffic governing signaling system of a type in which steady

energy or coded traffic governing energy is at times supplied to the first section at the end thereof remote from the intersection and at other times is supplied to the fourth section at the end thereof remote from the intersection, in combination, a coding device, a source of current, and electroresponsive means at each end of each of said second and third sections and at the ends of the first and fourth sections adjacent the intersection, each of said coding devices having contacts biased to a position in which they connect the associated electroresponsive device across the section rails and being movable on energization of the device to a position in which they connect the associated source of current across the section rails, the second and third sections each having at one end thereof means effective when the electroresponsive means at that end of the section and at the adjacent end of the adjacent section is not supplied with steady energy or coded energy to cause coded energy of a distinctive character to be supplied to the rails of such section, the electroresponsive means at each end of the second and third sections and at the ends of the first and fourth sections adjacent the intersection controlling energization of the coding devices at the adjacent ends of the adjacent sections to cause steady energy or coded traffic governing energy to be supplied to the rails of such sections according as steady energy or coded traffic governing energy is supplied to each of said electroresponsive means over the rails of the associated section, a crossing signal for said intersection, and means responsive to the supply of steady energy, coded traffic governing energy, or coded energy of said distinctive character over the rails of said second and third sections for controlling said crossing signal.

8. In crossing signal control means for use on a stretch of railway track over which traffic may move in either direction, the rails of said stretch being divided by insulated joints into a plurality of successive track sections including a first, a second, a third and a fourth section, the track stretch being intersected by a highway at a point in the stretch in the vicinity of the adjacent ends of the second and third track sections, the track stretch being equipped with a traffic governing signaling system of a type in which steady energy or coded traffic governing energy is at times supplied to the first section at the end thereof remote from the intersection and at other times is supplied to the fourth section at the end thereof remote from the intersection, in combination, a coding device, a source of current, and electroresponsive means at each end of each of said second and third sections and at the ends of the first and fourth sections adjacent the intersection, each of said coding devices having contacts biased to a position in which they connect the associated electroresponsive device across the section rails and being movable on energization of the device to a position in which they connect the associated source of current across the section rails, the second and third sections each having at the end thereof remote from the intersection means effective when the electroresponsive means at that end of the section and at the adjacent end of the adjacent section is deenergized to supply to the coding device at that end of the section energy effective to cause coded energy of a distinctive character to be supplied to the rails of such section, the electroresponsive means at each end of the second and third sections and at the ends of the first and fourth sections and at the ends of the first and fourth sec-

tions adjacent the intersection controlling energization of the coding devices at the adjacent ends of the adjacent sections to cause steady energy or coded traffic governing energy to be supplied to the rails of such sections according as steady energy or coded traffic governing energy is supplied to each of said electroresponsive means over the rails of the associated section, a cross-

ing signal for said intersection, and means responsive to the supply of steady energy, coded traffic governing energy, or coded energy of said distinctive character over the rails of said second and third sections for controlling said crossing signal.

JAMES J. VAN HORN.
